US0D1112462S

(12) **United States Design Patent** (10) **Patent No.:** **US D1,112,462 S**
(45) **Date of Patent:** **** Feb. 10, 2026**

(54) **CYMBAL**

(71) **Applicant:** **NINGBO KINLIN ELECTRONIC TECHNOLOGY CO., LTD.**, Ningbo (CN)

(72) **Inventor:** **Fuguo Wang**, Zhejiang (CN)

(73) **Assignee:** **NINGBO KINLIN ELECTRONIC TECHNOLOGY CO., LTD.**, Ningbo (CN)

(**) **Term:** **15 Years**

(21) **Appl. No.:** **35/520,065**

(22) **Filed:** **Jan. 31, 2024**

(80) **Hague Agreement Data**

Int. Filing Date: **Jan. 31, 2024**

Int. Reg. No.: **DM/235027**

Int. Reg. Date: **Jan. 31, 2024**

Int. Reg. Pub. Date: **Feb. 16, 2024**

(30) **Foreign Application Priority Data**

Dec. 28, 2023 (CN) 202330862059.1

(57) **CLAIM**

The ornamental design for cymbal as shown and described.

DESCRIPTION

1. Cymbal

1.1 : Perspective

1.2 : Perspective

1.3 : Front

1.4 : Back

1.5 : Left

1.6 : Right

1.7 : Top

1.8 : Bottom

Fig. 1.1 is a front top perspective view of the cymbal; Fig. 1.2 is a rear bottom perspective view thereof; Fig. 1.3 is a front elevational view thereof; Fig. 1.4 is a rear elevational view thereof; Fig. 1.5 is a left-side elevational view thereof; Fig. 1.6 is a right-side elevational view thereof; Fig. 1.7 is a top plan view thereof; Fig. 1.8 is a bottom plan view thereof. The broken lines where present illustrate portions of the cymbal that form no part of the claimed design.

1 Claim, 8 Drawing Sheets
